(57) **CLAIM**

We claim the ornamental design for an electronic device stand, as shown and described.

DESCRIPTION

FIG. 1 is a perspective view of an electronic device stand according to a first embodiment in a first orientation.

FIG. 2 is a first side view of the electronic device stand shown in FIG. 1.

FIG. 3 is a second view of the electronic device stand shown in FIG. 1.

FIG. 4 is a front view of the electronic device stand shown in FIG. 1.

FIG. 5 is a rear view of the electronic device stand shown in FIG. 1.

FIG. 6 is a top view of the electronic device stand shown in FIG. 1.

FIG. 7 is a bottom view of the electronic device stand shown in FIG. 1.

FIG. 8 is a perspective view of the electronic device stand according to the first embodiment in a second orientation.

FIG. 9 is a first side view of the electronic device stand shown in FIG. 8.

FIG. 10 is a second view of the electronic device stand shown in FIG. 8.

FIG. 11 is a front view of the electronic device stand shown in FIG. 8.

FIG. 12 is a rear view of the electronic device stand shown in FIG. 8.

FIG. 13 is a top view of the electronic device stand shown in FIG. 8; and,

FIG. 14 is a bottom view of the electronic device stand shown in FIG. 8.

The broken lines having equal segments represent portions of the article that form no part of the claimed design.

1 Claim, 12 Drawing Sheets
